UNITED STATES PATENT OFFICE.

WILLIAM H. WILKE, OF BERKELEY, CALIFORNIA, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

44,714.

Specification for Design.

Patented Sept. 30, 1913.

Application filed July 26, 1913. Serial No. 781,402. Term of patent 14 years.

To all whom it may concern:

Be it known that I, WILLIAM H. WILKE, a citizen of the United States, residing at Berkeley, in the county of Alameda and State of California, have invented a new, original, and ornamental Design for Handles for Spoons, Forks, or Similar Articles, reference being had to the accompanying drawings.

Figure 1 is a view of the obverse side of the handle, showing my design. Fig. 2 is a

view of the reverse side of the handle, and Fig. 3 is an enlarged detailed perspective view.

I claim—

The ornamental design for a handle for spoons, forks or similar articles, as shown.

WILLIAM H. WILKE.

Witnesses:

L. B. HASTE,
GEO. C. SAMPSON.
